CLAIM

The ornamental design for a portion control device for pets, as shown and described.

DESCRIPTION

FIG. 1 is a perspective view of a portion control device for pets showing my new design;

FIG. 2 is a top plan view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.
